DEMOUNTABLE CORNER SHELF

Marian A. Garris, Seattle, Wash.

Application December 22, 1947, Serial No. 793,132

3 Claims. (Cl. 211—148)

1

My present invention relates to the general art of shelf construction and, more particularly, to a demountable corner shelf.

Popular trends in interior decorating call, more and more, for the use of objects of art of the types made of glass, ceramics, or metal, to supplement the older forms of wall decoration, which were largely through the use of pictures of one sort or another. Further, in order to sustain interest and give the housewife an opportunity to change her decorative scheme at intervals, there has been an increasing demand for demountable shelving that can be put into use as occasion warrants, and then be taken down when not needed. Under such conditions, it is very desirable that the unit be easily demounted for storage. It is to supply this demand that I have created my demountable corner shelf.

The principal object of my present invention, therefore, is to provide a corner shelf that can be easily assembled and put into the position of use or disassembled for convenient storage.

A further object of my invention is to provide a demountable shelf which is so interlocking that the whole unit is a rigid, fixed shelf assembly that will not become loosened or dislodged so that valuable objects, or works of art, and the like, will not be placed in jeopardy or be damaged.

A further object of my present invention is to provide a demountable shelf for use in the corner of a room, and which lends itself to easy manufacture with the various types of sheet material now available.

Further objects, advantages and capabilities will be apparent from the description and disclosure in the drawings or may be comprehended or are inherent in the device.

In the drawings:

Fig. 1 is a perspective view showing one form of my shelf in its assembled form.

Figs. 2, 3, and 4, show progressive steps in the assembly of my demountable shelf with certain parts shown in section to better illustrate their construction, taken substantially along the line 3—3 of Fig. 1.

Fig. 5 is a fragmentary cross-sectional view taken along the broken lines 5—5 of Fig. 1.

Referring more particularly to the disclosure in the drawings, the numerals 10 and 12 designate, respectively, the two side members of demountable shelf. In outward appearance, these two shelf-supporting members are identical in outline, excepting that supporting member 10 must have additional material on the inner side so as to form the final corner se-

2

curing means, as is illustrated in Fig. 5, wherein it will be apparent that member 10 must be of sufficient increased size over member 12 so that it will overlap the same and provide for the final securing screws 14.

In my illustrations, I have shown, for use with the shelf supporting members 10 and 12, two shelves as 16 and 18. It will be apparent, it is believed, that any reasonable number of shelves might be used. The various shelves need not all be the same size or have the same outward contour, but the securing means which interlocks with the supporting members 10 and 12 must be of the same design and size, in order that assembly and disassembly can be achieved.

Each of the shelf members is provided with two bearing edges as 20 and 21. These two edges meet at 22 to complete the shelf proper and the included angle must correspond to the angle at which the two shelf supporting members 10 and 12 are disposed. This normally is a right angle but it will be apparent from the structure that this need not necessarily be true, as the construction can be made to conform to any angle less than a straight angle.

On each of the two edges 20 and 21 I provide an engagement member or tongue, as 23 and 24. These tongue members are undercut as at 26, and are beveled off at 28, so that they may be securely engaged within slots 30 and 32, cut respectively in the shelf supporting members 10 and 12, and as will best be observed in Figs. 1, 3 and 4, each of the slots are beveled at their ends; the bevel at 34 being so angled as to form a re-entrant angle and provide a firm engagement with the undercut portion 26 of the tongue members. Similarly, the opposite end 35 is beveled so as to accept, in snug engagement, the bevel 28 of the shelf member. It follows that the bevels and the spacing of the beveled surfaces must conform to the proportions of the tongue members 23 and 24, so that when fully engaged there will be intimate contact throughout the length and breadth of the tongue into slits 30 and 32 in the shelf supporting members.

In assembling my shelf structure, the shelves are positioned normally on edge, after the showing of Fig. 2. Then the two shelf-supporting members 10 and 12 are brought into position, so that beveled surfaces 34 may be engaged under their respective overhanging portions 26 of the tongue members. Then by an upward movement and by pressing in the top of the shelves, as indicated by arrows 36 and 37 in Fig. 3, tongues 23 and 24 are fully entered into their corresponding

slots 30 and 32 in the shelf-supporting members and the surfaces or edges 20 and 21 are in firm engagement with the shelf members, as is probably best illustrated in Figs. 1 and 4.

In this assembled position, if the shelf unit were to be placed immediately into the corner of the room and secured there, the entire device would be locked so that its various members could not loosen or separate. However, it has been found most convenient to provide that the shelf be a rigid unit even before being placed in a corner, and to achieve this, I have provided a plurality of securing screws 14, which are passed through the overlapping shelf-supporting member 10 and threaded into the companion support member 12 that is probably best illustrated in Fig. 5. When so arranged, the unit is so locked in that any handling, such as might occur in the final placement of the device, will not loosen any of the parts. For convenient hanging of the shelf, I provide a plurality of screw holes as 39.

It is believed that it will be apparent from the above description and the disclosure in the drawings that the invention comprehends a novel construction of a demountable corner shelf.

Having thus described my invention, I claim:

1. A demountable corner shelf, consisting of: two shelf supporting members adapted to form an angle by abutting along a common line; means for securing said members in their abutting relationship; said shelf supporting members adapted to lie in intimate contact with the walls forming the corner in which the shelf is to be used; a plurality of shelf members having an interior angle formed by the sides adapted to engage said shelf supporting members; said shelf supporting members having co-acting slits, one in each member, disposed in the same horizontal plane; said slits having their ends beveled so they are directed toward the line of abutment of said shelf supporting members; said shelf members having tongues extending outwardly from their sides forming the interior angle and of a length substantially equal to and adapted to co-act with the slits in said shelf supporting members; said tongues having their inner ends beveled at an obtuse angle to co-act with the inner end bevels of said slits and having the outer ends cut with a re-entrant angle to co-act with the outer end of the said slits to form an interlocking securing means for said shelf members when the shelf unit is assembled as a whole.

2. A demountable corner shelf, consisting of: two shelf supporting members adapted to form an angle by abutting along a common line; screw

means, spanning the common line, for securing said members in their abutting relationship; said shelf supporting members adapted to lie in intimate contact with the walls forming the corner in which the shelf is to be used; a plurality of shelf members having an interior angle formed by the sides adapted to engage said shelf supporting members; said shelf supporting members having co-acting slits, one in each member disposed in the same horizontal plane; said slits having their outer ends beveled so they are directed toward the line of abutment of said shelf supporting members; said shelf members having tongues extending outwardly from their sides forming the interior angle and of a length substantially equal to and adapted to co-act with the slits in said shelf supporting members; said tongues having their outer ends cut with a re-entrant angle to co-act with the outer end of the said slits to form an interlocking securing means for said shelf members when the shelf unit is assembled as a whole.

3. A demountable corner shelf, consisting of: two shelf supporting members adapted to form an angle by abutting along a common line; said shelf supporting members adapted to lie in intimate contact with the walls forming the corner in which the shelf is to be used; a plurality of shelf members having an interior angle formed by the sides adapted to engage said shelf supporting members; said shelf supporting members having co-acting slits, one in each member disposed in the same horizontal plane; said slits having their outer ends beveled so they are directed toward the line of abutment of said shelf supporting members; said shelf members having tongues extending outwardly from their sides forming the interior angle and of a length substantially equal to and adapted to co-act with the slits in said shelf supporting members; said tongues having their outer ends cut with a re-entrant angle to co-act with the outer end of the said slits to form an interlocking securing means for said shelf members when the shelf unit is assembled as a whole.
